UNITED STATES PATENT OFFICE.

CHARLES NEMETHI, OF LOS ANGELES, CALIFORNIA, ASSIGNOR TO PREMO SPECIALTY MANUFACTURING COMPANY, OF LOS ANGELES, CALIFORNIA, A CORPORATION OF CALIFORNIA.

DISPENSING DEVICE.

984,592.

Specification of Letters Patent. Patented Feb. 21, 1911.

Application filed December 20, 1909. Serial No. 534,112.

To all whom it may concern:

Be it known that I, CHARLES NEMETHI, a citizen of the United States, residing at Los Angeles, in the county of Los Angeles and 5 State of California, have invented new and useful Improvements in Dispensing Devices, of which the following is a specification.

This invention relates to dispensing devices embodying a magazine in which a 10 quantity of the articles to be dispensed are placed, and comprising a device of improved form for permitting the articles to be delivered from the magazine for use. The device is particularly useful for dispensing 15 drinking straws at a soda fountain, and the delivery mechanism of the device is constructed with the special object of keeping the straws in parallel arrangement and preventing the straws from choking the delivery chute.

The invention consists in the construction and combination of parts to be more fully described hereinafter and particularly set forth in the claims.

25 In the annexed drawing which fully illustrates my invention, Figure 1 is a front elevation of the device. Fig. 2 is a plan. Fig. 3 is a vertical section through the device taken on the line 3—3 of Fig. 2. This 30 shows the parts of the device in their normal position or relation. Fig. 4 is a vertical section taken at one side of the device showing it in operation and indicating the way in which the articles are delivered.

35 Referring more particularly to the drawing, 1 represents the body of the device which is in the form of a magazine having metal end walls 2 and side plates 3 of glass or similar material held in position by the 40 end walls as indicated. On the side of the magazine longitudinally extending side bars 4 are formed beneath which delivery openings 5 are placed. The bottom 6 of the magazine comprises an inner plate 7 the 45 edges of which are formed into upwardly and inwardly inclining flanges 8. Extending longitudinally in the openings 5 delivery shelves 9 are provided. These shelves have bodies in the form of inclined plates or 50 doors 10 which rest near their upper edges against the upper edges of the openings 5 so as to close these openings as indicated. In addition to this, each delivery shelf presents an inwardly extending flange 11 which 55 is disposed nearly at right angles to the

plate 10. At the angle or meeting edge between the flange 11 and the plate 10 a spindle 12 is formed the ends of which are rotatably mounted in the end walls 2 of the magazine. At one end of the magazine this 60 spindle extends through the end wall and is bent upwardly so as to form a thumb lever 13 for rotating the delivery shelf. These thumb levers 13 are arranged oppositely, that is, one of them is disposed at the right 65 end of the machine as viewed in Fig. 1, while the other is disposed at the left end of the device. The edges of the flanges 11 are provided with inwardly and downwardly extending fingers 14 the purpose of 70 which will appear more fully hereinafter. Within the magazine and near the end walls 2 bracket plates 15 are mounted in a transverse position, the lower ends of said bracket plates being provided with flanges 16 which 75 are secured to the bottom of the magazine as indicated. Between these plates 15 and the end walls 2 springs 17 are attached which are secured to the dispensing shelves 9 and hold the same so that they normally close 80 the openings 5 as will be readily understood. The bracket plates 15 present inclined edges 18 which form a meeting angle 19 substantially in the plane of the central axis of the magazine. Near their upper edges, the 85 plates 15 are provided with openings 20 which support a hinge bar 21 which extends longitudinally of the magazine in the lower part thereof as shown most clearly in Fig. 2. On this hinge bar 21 feed frames 22 are 90 mounted. Each of these feed frames comprise arms 23 which form eyes 24 around the hinge bar from which they extend transversely of the body. At the outer ends of these arms 23 feed bars 25 are rigidly attached. These feed bars 25 are in the form of elongated plates 26, the extremities of 95 which are normally supported on the edges 18 of the bracket plates. On the lower edge of each plate 26, a downwardly extending chute plate 27 is formed which is normally disposed in a substantially vertical plane as indicated in Fig. 3. The lower edge of this chute plate 27 is formed with an inwardly and downwardly extending flange 28. Between the chute plate 27 and the bar 4 at 100 each side of the magazine, a narrow feed chute is formed and the straws 29 are adapted to descend into the chute as indicated. On the inner sides of the bars 4 guards 105 30 110

are formed of substantially triangular cross section which extend longitudinally of the magazine, and having inclined lower faces. The inner edges of these bars lie near the 5 feed bars 25. The body or magazine 1 is supported at a slight elevation above the counter or table by means of legs 31 arranged as shown.

The mode of operation of the device will 10 appear most clearly from inspection of Fig. 4. When either of the thumb levers 13 is depressed the delivery shelf to which it is attached is rocked as indicated in Fig. 4 so that the straw which normally lies in the shelf 15 at the bottom of the feed chute will roll down the plate 10 on to the holder 6^a. As this rotation takes place the fingers 14 move upwardly on the interior and engage the flanges 28 so as to elevate the feed frames 20 toward the position indicated. In this way these fingers close off the upper part of the chute so as to prevent any of the straws from descending and they also agitate the body of straws so as to facilitate the feed and 25 straighten them with respect to each other. In this connection it should be understood that the feed frames 22 are loosely mounted on the hinge rod 21 so that they can be raised freely by the fingers 14 of the delivery shelves.

Having described my invention, what I claim as new and desire to secure by Letters Patent is:

1. In a device of the class described, in 35 combination, a magazine having a delivery

opening in the wall thereof, bracket plates mounted within said magazine and having inclined edges, a feed frame supported on said inclined edges and having a hinged connection at the upper edge thereof, a delivery door disposed in said delivery opening, means for actuating said delivery door to deliver the articles one by one, means carried by said delivery door for raising the free edge of said feed frame, said bracket 40 plates being disposed near the end walls of said magazine, and springs disposed between said bracket plates and said end walls and connected with said delivery shelf to keep said delivery opening normally closed. 45

2. In a device of the class described, in combination, a magazine having a pair of oppositely disposed walls with delivery opening formed therein, a hinge rod extending longitudinally of said magazine, feed frames 55 having hinged connection with said hinge rod and inclining downwardly in the direction of said delivery openings, means for delivering articles one by one from said delivery openings, and automatic means for 60 elevating the outer edges of said feed frames to accelerate the feeding movement.

In witness that I claim the foregoing I have hereunto subscribed my name this 11th day of December, 1909.

CHARLES NEMETHI.
